UNITED STATES PATENT OFFICE.

HARRY A. ANDERSEN, OF JAMAICA, NEW YORK.

REINFORCING DEVICE FOR SUPPORTING MATERIAL AROUND BEAMS.

1,208,886.

Specification of Letters Patent. Patented Dec. 19, 1916.

Application filed October 31, 1914. Serial No. 869,595.

To all whom it may concern:

Be it known that I, HARRY A. ANDERSEN, a citizen of the United States, and resident of Jamaica, in the county of Queens and 5 State of New York, have invented a new and Improved reinforcing Device for Supporting Material Around Beams, of which the following is a specification.

This invention relates to improved means 10 for supporting the concrete protection around the flanges of beams in buildings and other structures and has for its object the obtaining of an efficient and economical supporting device.

15 In the construction of building floors where steel beams are used, the method most commonly used consists of a terra cotta or a concrete slab or arch placed between, and supported upon the flanges of the adjoining beams. In order to fireproof the bottom flanges of the beams they are also protected with terra cotta or concrete. In the case where concrete is used, it is found rather troublesome to make the concrete adhere to 25 the bottom flange of the beam. To overcome the objectionable feature, wires are used bent over the flanges and spaced about twelve inches apart. In this method it is found that the concrete, while being poured into the 30 form, forces the wire up against the bottom flange of the beam and thus a good bond is not obtained between the painted surface of the flange of the beam and the concrete. Another difficulty encountered, is to keep the 35 wires properly spaced. A somewhat better method employed, is the use of expanded metal or wire mesh around the flanges of the beams, but these methods still retain some of the objectionable features mentioned above 40 and are more expensive. My new and improved reinforcing device or flange clip eliminates the above objectionable features by being made of a definite shape and size, while its projecting flange by being hooked over 45 the flange of the beam assures a definite position for same and it cannot readily be displaced.

One of the many advantages of my invention is that the clip, being provided with a 50 web and top and bottom flanges, really forms a small beam, thereby providing a very strong support for the protection concrete, furthermore, the top flange of the clip by pressing against the flange of the beam provides a rigid support for the clip which will 55 not be displaced when the concrete is being

poured, while the shape of the bottom is such as to provide a support for the concrete slab on both sides of the clip, thereby supporting the concrete without depending upon any 60 adhesion of the concrete to the flange of the beam.

Another feature of my invention is that when the clips are hooked over the flanges and the forms placed and the concrete poured 65 in, the weight of the concrete by pressing down upon the bent over clip and being surrounded with the adjoining concrete provides a very strong support for the slabs.

A further advantage of my invention is 70 that where a flat ceiling construction is desired, the slab may be cast on the ground in the following manner: The wire reinforcement or any other form of reinforcing material used, is laid out on smooth boards 75 placed on the ground, the clips are then placed at the required distances apart and the concrete slab is then cast. After the slab has set, the entire slab is lifted and the clips hooked over the flanges of the beams 80 thus forming a suspended ceiling. In some cases, this form of ceiling may also be used as a form for pouring the floor concrete.

Another advantage of my invention is that 85 it may be used to repair portions of beam flanges not properly protected, in which case the concrete is cut away to the required width, a pair of clips are then hooked over the flange of the beam and then concrete is 90 packed in between.

Another advantage of my device is that in a case where it is desired not to delay the construction work and the clips or other form of reinforcement cannot be obtained in time, the forms may be built in place and 95 the clips hooked into position from the top after the forms are built. This could not be done so well with any other form of reinforcement.

Another feature of my invention which 100 makes it very economical, is, that it is stamped from one sheet of metal.

Other advantages of my invention will be apparent from the detailed description and the accompanying drawing forming a part 105 of this specification in which like numerals correspond to similar parts in all the views, in which—

Figure 1 is a longitudinal elevation of an I beam showing the clips hooked over the bottom flange and the concrete in place. Fig. 2 shows a cross section of an I beam 110

flange with the clip hooked over. Fig. 3 is a section on line 3—3 of Fig. 2. Fig. 4 is longitudinal view of the clip before the upper flanges of the clip are bent over the 5 flanges of the beam. Fig. 5 is a section taken on line 5—5 of Fig. 4, while Fig. 6 is a view showing the clip hooked over the beam and the concrete protection around it.

Referring to Figs. 3, 4 and 5, my device 10 consists of a sheet of metal formed into the web 13, the upper flange 9, approximately at right angles to the web 13 and the bottom flanges 14 and 15 joined by a short web as shown in Figs. 3 and 5. The slots 11 are 15 cut in at the junction of the web 13 and the flange 9 leaving the portions 8 of the flange 9 projecting beyond the edges 7. The distance between the points 12, the innermost portions of the grooves 11, is varied to correspond to the various widths of beam 20 flanges used. The projecting portions 8 of the flange 9 are adapted to be bent over the flanges of the beam 6, thus fastening the clip to the beam.

Referring to Fig. 1, it will be noted that 25 after the clip is hooked into place, the flange 14 forms a support for the concrete slab on one side while the flange 15 forms a support for the concrete slab on the other side. If 30 it be desired to space the clips farther apart than the thickness of concrete will permit, reinforcing rods 10 may be inserted in the slots 16 thereby forming a reinforced slab between the adjoining clips as is clearly 35 shown on the right side of Fig. 1. The holes 17 serve to provide additional bond between the concrete and the form. An alternative method of making my form is that

the shape may be made of wire mesh instead of sheet metal.

The form described embodies my preferred form, however several modifications may be made employing the same general principle. I do not wish to limit myself to the exact form disclosed, but wish to include 45 all forms embodying this principle.

Having thus disclosed my invention, I claim as new and wish to secure by Letters Patent.

1. A reinforcing support for the protection material around a beam, comprising an upper flange with free ends adapted to be bent around the beam, a main web integral with said flange, and two lower flanges one above the other, a second web integral with 55 and connecting said lower flanges to each other, the upper flange of said lower flanges being integral with said main web.

2. A reinforcing support for protection material around a beam, comprising an upper flange with free ends adapted to be bent around the beam, a perforated main web integral with said flange, and two lower flanges one above the other, a perforated second web integral with and connecting said 65 lower flanges to each other, the upper flange of said lower flanges being integral with said main web.

Signed at New York in the county of New York and State of New York this 28th day 70 of October, 1914.

HARRY A. ANDERSEN.
